UNITED STATES PATENT OFFICE

JOEL SAMUEL FRIES, OF HELENELUND, SWEDEN, ASSIGNOR TO AKTIEBOLAGET SVENSKA SPIRALFABRIKEN, OF STOCKHOLM, SWEDEN, A MANUFACTURING COMPANY OF SWEDEN

LAMINATED SPRING

Application filed June 30, 1928, Serial No. 289,529, and in Sweden July 7, 1927.

The present invention relates to an improvement in laminated supporting springs of the type which consist of two or more spring leaves or plates placed on top of each other and having a substantially rectangular cross sectional shape. In order in such springs to prevent lateral displacement of the spring plates relatively to each other, said plates are often provided with longitudinal 10 projections or ridges.

The present improvement consists principally in that each spring plate is provided with longitudinal projections or ridges on both sides, said ridges having such height 15 and such size that the maximum stresses on both sides of the spring plate become equal or substantially equal and thus become decreased as far as possible. This arrangement may suitably be carried out in such 20 manner that each spring plate is provided on one side with two longitudinal projections or ridges, one along each edge, and on the other side with two longitudinal projections or ridges at a distance from the edges such that 25 when the spring plate is placed against a second spring plate said last mentioned projections or ridges come between the ridges at the edges of the second plate. By this 30 engagement the ridges will thus prevent lateral displacement of the plates relatively to each other.

In the accompanying drawings, Fig. 1 shows a cross section of two spring plates having ridges as heretofore used, whereas 35 Figs. 2 to 5 show cross sections of various forms of springs having two spring plates according to the present improvement.

As shown in Fig. 1, it has heretofore been customary to provide each spring plate 1 on one side, and in the middle thereof, with a longitudinal ridge 2 which engages a corresponding groove 3 in the adjacent spring plate when the spring plates are placed against each other. By making the spring 45 plates with a ridge on one side and a groove on the other, in this manner, the moment of inertia with respect to the neutral line $a-a$ suffers only a hardly appreciable change, whereas the moment of resistance 50 with which one has to calculate, is decreased

to a considerable degree, so that, for instance, for a spring plate having the cross sectional dimensions 90 x 13 mm. it is decreased by no less than 29 per cent as compared with the same moment of a corresponding spring 55 plate having a quite rectangular cross section, without ridge or groove. The capacity of the spring is therefore decreased by no less than about 50 per cent, and breaks will easily occur at the top of the ridge 2 since at 60 this point the fiber stress becomes very great.

These difficulties are remedied by the present invention.

In the embodiment of the invention illustrated in Fig. 2, each spring plate 4 is provided on one side with two longitudinal projections or ridges 5, one at each edge, and on the other side with two longitudinal projections or ridges 6 which are located at such 65 distance from the edges of the spring plate that, when the spring plate is placed against another spring plate, said ridges 6 on the first plate come between the ridges 5 at the edges of the second spring plate. Through 70 this engagement the ridges 5 and 6 will thus prevent lateral displacement of the spring plates relatively to one another, in the same manner as the ridges 2 and grooves 3 in Fig. 1.

In the construction shown in Fig. 2 the 75 ridges 5 have the same width and height as the ridges 6, as a result of which the distance b from the upper face of the ridges 5 to the neutral line $a-a$ becomes equal to the distance c between said line and the lower face 80 of the ridges 6, and the maximum stresses become equal and therefore also as small as possible on both sides of the spring. The 85 risk of spring fracture is therefore decreased, and the capacity as well as the life of the 90 spring are increased. In this embodiment each ridge 5 or 6 has a width equal to one-sixth of the width of the entire spring plate. Tests have proved that this construction 95 gives the best elasticity possible. The space 7 between the inner ridges 6, and which may 100 suitably be utilized for supplying lubricant to the sliding surfaces of the spring plates, thus obtains a width equal to one-third of the entire width of the spring plate. The

side surfaces of the ridges are preferably made with slightly different radii of curvature, in such manner that narrow spaces 8 are formed between the same which likewise 5 may serve for supplying lubricant.

According to Fig. 3, the ridges 6 on the lower side of each spring plate have the same height as the ridges 5 on its upper side, but a greater width. The neutral line $a-a$ is, 10 therefore, moved slightly downwards, that is, in the direction towards the wide ridges 6, so that the distance b' becomes somewhat greater than the distance c' .

This is also the case in the construction 15 illustrated in Fig. 4, which only differs from that shown in Fig. 3 in that the depth of the recess or groove 7 between the two inner ridges 6 is slightly decreased, which results in the neutral line being displaced still more 20 downwards.

The construction illustrated in Fig. 5 corresponds substantially to that illustrated in Fig. 2, the ridges 5 and 6 in Fig. 5 having equal height and width, but it differs from 25 the construction shown in Fig. 2 in that the width of the ridges 5 and 6 is somewhat smaller in proportion to the width of the entire spring plate.

I claim:

30. 1. In a laminated spring, the combination of at least two spring plates bearing against each other and each having a substantially rectangular cross section, each spring plate having longitudinal ridges on both sides projecting outside the rectangular cross section of the plate, said ridges on one side of each plate running along the edges of the plate, and said ridges on the other side of each plate running at a distance from the edges of the 35 plate equal to the width of the ridges on the first named side of the plate, said ridges having such height and such size that the maximum stresses become substantially equal on both sides of the spring plate.
40. 2. A laminated spring as claimed in claim 1, in which each ridge has a width substantially equal to one-sixth of the width of the spring plate.
45. 3. In a laminated spring, the combination of at least two spring plates bearing against each other and each having a substantially rectangular cross section, each spring plate having on each side two longitudinal ridges projecting outside the rectangular cross section of the plate and separated by a groove, the distance between the inner edges of the two ridges on the one side of the spring plate being substantially equal to the width across the outer edges of the two ridges on the other side of the spring plate so that when one 50 spring plate is placed against a second spring plate the inner edges of the ridges on one side of the first plate bear against the outer edges of the ridges on the other side of the second plate, said ridges on each spring plate hav-

ing such height and such size that the maximum stresses on both sides of the spring plate become substantially equal.

4. A spring plate having a substantially rectangular cross section and having on each side two longitudinal ridges projecting outside the rectangular cross section of the plate and separated by a groove, the ridges on the one side of the spring plate being displaced relatively to the ridges on the other side of the spring plate in such manner that a ridge on one side is not opposed by a ridge on the other side, said ridges having such height and such size that the maximum stresses on both sides of the spring plate become substantially equal.

5. A spring plate having a substantially rectangular cross section and having on each side two longitudinal ridges projecting outside the rectangular cross section of the plate and separated by a groove, the distance between the inner edges of the two ridges on the one side of the spring plate being substantially equal to the width across the outer edges of the two ridges on the other side of the spring plate, said ridges having such height and such size that the maximum stresses on both sides of the spring plate become substantially equal.
